US0D1093346S

(12) **United States Design Patent** (10) **Patent No.:** **US D1,093,346 S**
(45) **Date of Patent:** **** Sep. 16, 2025**

(54) **TV REMOTE CONTROL**

(71) Applicant: **TIANCHANG XINGYANG ELECTRONIC TECHNOLOGY CO, LTD.**, Tianchang (CN)

(72) Inventor: **Yang Yang**, Tianchang (CN)

(73) Assignee: **TIANCHANG XINGYANG ELECTRONIC TECHNOLOGY CO, LTD.**, Tianchang (CN)

(**) Term: **15 Years**

(21) Appl. No.: **29/924,703**

(22) Filed: **Jan. 19, 2024**

(51) LOC (15) Cl. **14-03**

(52) U.S. Cl.

USPC **D14/218**

(58) **Field of Classification Search**

(57) **CLAIM**

The ornamental design for a TV remote control, as shown and described.

DESCRIPTION

FIG. 1 is a front perspective view of a TV remote control, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 2.

The broken lines in the drawings illustrate the portions of the TV remote control, which form no part of the claimed design.

The dash-dot-dash broken lines encircling the enlarged views are for annotative purposes only and form no part of the claim thereof.

1 Claim, 10 Drawing Sheets
